REFRIGERATOR

Filed Sept. 16, 1930

Rudolf Schlenk INVENTOR

BY
OTTO MUNK ATTORNEY

UNITED STATES PATENT OFFICE

RUDOLF SCHLENK, OF VIENNA, AUSTRIA

REFRIGERATOR

Application filed September 16, 1930, Serial No. 482,322, and in Austria September 17, 1929.

This invention relates to a new and improved type of refrigerator and aims at the attainment of a number of advantages over existing types by virtue of the peculiar arrangement of the parts by which it is characterized. The refrigerator in accordance with the invention has a rigidly fixed lid, while the body or case proper is adapted to be lowered away from the lid. The ice chamber or refrigerating machine is structurally united to the lid. In the closed condition the horizontal upper edge of the body or case is in contact with the under surface of the lid, so that the cold air tends of itself to remain in the pot-shaped body and no special arrangement for forming a tight joint between body and lid is necessary. Doors and locks can be dispensed with, so that the costs of production are greatly diminished. The refrigerator is opened by the lowering of the pot-shaped body away from the lid, which arrangement implies a saving of cooling material or energy, since the cooled air within the refrigerator has no tendency to escape from the pot-shaped body but is lowered together with the latter when the refrigerator is opened.

One form of the invention is shown by way of example in the accompanying drawing, 30 in which:—

Fig. 1 shows a refrigerator in accordance with the invention, partly in longitudinal section and partly in elevation.

Fig. 2 is a section taken on the line II—II 35 of Fig. 1 through the supporting device for the contents of the refrigerator.

1 designates the vessel receiving the liquid to be evaporated, 2 the pump serving for removing and compressing the air vapor mixture. From the pump a conduit leads to the condensation water collector (not shown). The vessel 1 contains the medium to be evaporated (volatile substances such as oils, benzine, ether, methylalcohol, etc.). From the vessel 1 a conduit 3 leads to the pump 2 from which another conduit runs to the condensation water collector. 13 is the immovable lid, and 14 the receptacle body or case proper of the refrigerator, this body being adapted to be lowered while the parts 1, 2, 3 are struc-

turally united to the fixed lid. The lowering and raising of the body 14 is effected with the help of a simple counterweight arrangement consisting of a set of pulley-wheels 15 and a counterweight 16.

It is advantageous to attach the ice chamber or refrigerating machine to the under side of the lid in such a manner that it occupies a position in the upper part of the cooling chamber when the refrigerator is closed. This arrangement leads to further economy, since the coldest air trickles down over the articles to be cooled, becomes warmed, and then rises up the walling of the refrigerating chamber. The inner surface of the walling is thus swept by the relatively warmest air, which implies a reduction in the loss of cold.

The employment of the above-mentioned simple counterweight system consisting of a pulley set 15 and a counterweight 16 presupposes that the goods to be chilled are not carried by the body of the refrigerator. It is therefore advisable to load the goods to be chilled on special supporting devices 32 attached to the fixed lid.

It is further advisable to subdivide the supporting device into stages or platforms 38, 39, and 40, and to provide openings 42 in the upper stages to facilitate the accommodation of particularly high objects (for example long-necked bottles).

Moreover certain of the stages may be so constructed as to occupy only a portion of the cross-sectional area of the interior of the refrigerator, as shown in the drawing in the case of the stage 39.

The refrigerator described above and illustrated in the accompanying drawing represents only an example of a form of construction embodying the present invention. The refrigerator and its details are capable of modification within the scope of the disclosed invention.

I claim:—

1. In a refrigerator the combination with a fixed immovable lid and a receptacle adapted to be lowered away from the said lid, and means for cooling the interior of the said receptacle, which means is attached to the said

lid and so located as to occupy a position in the interior of the said receptacle when closed against the said lid.

2. In a refrigerator the combination with 5 a fixed immovable lid and a receptacle adapted to be lowered away from the said lid, platforms disposed at varying distances from the said lid and adapted to be enclosed within the said receptacle, means for the attachment 10 of the said platforms to the said lid, and openings in those of the said platforms which are nearest to the said lid.

In testimony whereof I affix my signature.
RUDOLF SCHLENK.
